UNITED STATES PATENT OFFICE.

JUNIUS B. IRVING, OF KANSAS CITY, MISSOURI, ASSIGNOR OF ONE-HALF
TO JOSEPH D. HAVENS, OF SAME PLACE.

LOOSE-SHEET HOLDER.

SPECIFICATION forming part of Letters Patent No. 681,653, dated August 27, 1901.

Application filed March 31, 1900. Serial No. 10,900. (No model.)

To all whom it may concern:

Be it known that I, JUNIUS B. IRVING, a citizen of the United States, residing in Kansas City, in the county of Jackson and State of Missouri, have invented a certain new and useful Improvement in Loose-Sheet Holders, of which the following is a specification, reference being had therein to the accompanying drawings.

10 My invention relates to improvements in loose-sheet holders.

It has for its object the providing of a holder to be used for retaining loose sheets—such as invoices, bills, &c.—in a shape convenient for inspection, while at the same time permitting the ready extraction or insertion of one or more sheets within the holder.

15 With most of such sheet-holders as are commonly used inspection of the extreme upper end of the sheet is rendered difficult and the insertion or extraction of single sheets is accomplished with considerable trouble. With my invention this annoying feature is wholly obviated.

20 My invention provides two sheet-holding members hinged together in such a manner that one member may be swung so as to remove it wholly from covering the sheets held in the holder, thereby permitting inspection 30 of the whole length of the loose sheets and the insertion or removal of one or more sheets without disturbing the others.

25 My invention provides further means by which the members are retained when swung to the open position and means for holding them together when in the closed position.

35 My invention provides further certain novel and useful features of construction herein-after fully described and claimed.

40 In the accompanying drawings, which illustrate my invention, Figure 1 represents a plan view showing the members in the open position. Fig. 2 represents a vertical sectional view taken on the dotted line *a b* of Fig.

45 1. In this figure the loose sheets are represented by dotted lines. In this view the sheet-holding members are shown in the closed position. Fig. 3 represents a similar view to that shown in Fig. 2, the cover, however, being shown in the closed position. Fig. 4 represents a view similar to that shown in Fig.

2, excepting that the members are shown in the fully-open position. Fig. 5 represents a central vertical sectional view of the hinge employed in carrying out the principles of my invention. In this view the hinge is shown in the open position, the spring resting upon the barrel or cylindrical part of the opposite member. Fig. 6 represents one form of pintle used with a hinge of my invention. Fig. 7 represents an end view of the hinge. Fig. 8 represents a view similar to that shown in Fig. 5, excepting that the hinge is shown in the closed position. Fig. 9 represents a plan view of the hinge in the open position.

Similar letters of reference indicate similar parts.

A indicates the stationary sheet-holding member, which may be of any suitable material having some rigidity, preferably. Cardboard is an acceptable material for general use. B indicates the swinging sheet-holding member. The two members have a swinging or a hinge connection with each other, comprising, preferably, two hinges, (indicated in a general way in the drawings by the letter C.) Each hinge consists of two members designated, respectively, by D and E. They are formed in the ordinary manner, with the following novel exceptions: The two parts D and E are each provided with the ordinary barrel or cylindrical shaped portions, in which the pintle F is located, on which the parts swing in a pivotal manner. The part D is provided with a spring portion G, which is adapted to lie with considerable pressure upon the barrel portion of the part E and serves as a brake for preventing pivotal movement between the two parts of the hinge. The spring G extends beyond the outer periphery of the pintle F and is adapted to enter a notch provided in the pintle F and indicated by H at such times as the part E has been swung into the closed position. A corresponding notch I is provided in the barrel portion of the part E, so that when the said part is in the closed position, as shown in Figs. 2, 3, and 8, the spring will have a pressure exerted upon the said part tending to force it toward the part D and resisting any tendency of the parts to regain the open position. It will be noted that the outer end

of the spring G when the parts are in the closed position extends considerably beyond the outer periphery of the pintle. It is designed to have the spring extend, as shown in Figs. 1 and 9, to near the center of the pintle, so that in swinging the part E of the hinge the end of the spring will not cut into or abrade the material composing the part E. The spring G is preferably integral with the part D; but it may be a separate piece, if desired. The member A is secured in any desirable manner to the parts D of the hinges. The part E of the hinge is provided at a suitable distance from the cylindrical portion with a right-angled extension J. The said extension is disposed upwardly, as shown, and the member B is secured rigidly in any desired manner to the two extensions with which the two hinges are provided.

To the upper end of the member B, as viewed in Fig. 4, is hinged a flap or cover K by means of a strip, preferably of leather or cloth and indicated by L. To prevent the cover being stripped from the leather hinge, I find it desirable to provide a supplemental hinge or strip M, disposed upon the opposite side of the cover and inner side of the member B. This strip M is of thin material, such as cloth, and does not prevent the ends of the cover and the member B from abutting against each other when the cover is swung against the member B in the closed position. The entire structure may be covered over with a cloth binding, if desired, to give the holder a suitable appearance.

In operating my invention the cover or flap K is first swung into the position shown in Fig. 2 and then by forcing it farther rearward it will bear upon the upper side of the member B, causing it to swing together, with the parts E of the hinges into the position shown in Fig. 4, or what I term the "open" position. The springs G, bearing upon the parts E, will hold the parts in position, and the loose sheets may be inserted, extracted, or examined at will. To close the device, the cover is swung forward until its hinged end abuts against the upper edge of the member B, which by continued forcing forward of the cover will be forced to swing on the hinges C until the springs G enter the notches I of the parts E of the hinges. The tension of the said springs will then tend to further close the parts and also resist their separation, and the members A and B will be forced tightly together and will hold such sheets as may be inserted between them. For general inspection the cover K may be swung upon the hinge-strip L into the position shown in Fig. 2. If it is desired to insert a sheet, to extract, or to examine one more fully, the operation above described may be resorted to.

If desired, the pintle may be composed of two pieces instead of a single notched one. Such a construction is shown in Fig. 9, the two parts of the pintle being shown in dotted

lines. In such a modification the inner ends of the parts composing the pintle should not extend beyond the notch with which the part E is provided. A recess will thus be provided which will be the equivalent of the notch in the pintle and will permit the spring G to rest upon the part E when the hinge is in the closed position. Various other modifications in construction may be made without departing from the spirit of my invention.

Having thus described my invention, what I claim, and desire to secure by Letters Patent, is—

1. In a loose-sheet holder, the combination with two sheet-holding members, of a hinge connecting them comprising two parts having cylindrically-formed portions embracing a common pintle, a notch being provided in the cylindrical portion of one part of the hinge, and a spring on the other part normally bearing upon the cylindrical portion of the opposite part and adapted to enter the notch when the members have been swung toward each other to a certain position, substantially as described.

2. In a loose-sheet holder, the combination with two sheet-holding members, of a hinge connecting them comprising two parts embracing a common pintle, the pintle being provided with a notch, and one of the parts of the hinge being also provided with a notch, and a spring on the other part adapted to enter the two notches when the members have been swung to a certain position, substantially as described.

3. The combination with two sheet-holding members, of a cover hinged to one of the members, a hinge connecting the two members comprising two parts having cylindrically-formed portions embracing a common pintle, a notch being provided in the cylindrical portion of one part of the hinge, and a spring on the other part adapted to enter the said notch when the members have been swung to a certain position, substantially as described.

4. The combination with two sheet-holding members, of a hinge connecting the two members comprising two parts having cylindrically-formed portions embracing a common pintle, a spring on one part which bears upon and resists rotation of the other part on the pintle when the members are swung to a certain position, and means by which the spring tends to rotate the said part when the members are in a different position, substantially as described.

5. The combination with two sheet-holding members, of a plurality of hinges connecting the two members each hinge comprising two parts having cylindrically-formed portions embracing a common pintle, a spring on one part which bears upon and resists rotation of the other part on the pintle when the members are swung to a certain position, and

means by which the spring tends to rotate the said part when the members are in a different position, substantially as described.

6. The combination with two sheet-holding members of a plurality of hinges connecting them, each hinge comprising two parts having cylindrically-formed portions embracing a common pintle, a notch in the cylindrical part of one part, and a spring on the other part adapted to engage the said notch when the members have been swung to a certain position, substantially as described.

7. The combination with two sheet-holding members, of a hinge connecting the two members comprising two parts having cylindrically-formed portions embracing a common pintle, a notch in the cylindrical part of one part, and a spring on the other part adapted to enter the said notch when the members have been swung to a certain position, substantially as described.

8. The combination with two sheet-holding members, of a hinge connecting the two members comprising two parts having cylindrically-formed portions embracing a common pintle, a notch in the cylindrical part of one part and a resilient tongue integral with the other part and adapted to enter the said notch when the members have been swung to a certain position, but bearing upon and serving to prevent rotation of the opposite part when the members have been swung to a position in which the tongue is disengaged from the said notch, substantially as described.

9. The combination with two sheet-holding members, of a plurality of hinges connecting them, each hinge comprising two parts having cylindrically-formed portions embracing a common pintle, a notch in the cylindrical part of one part, and a resilient tongue on the other part adapted to engage the said

notch when the members have been swung to a certain position, substantially as described.

10. The combination with two sheet-holding members, of a plurality of hinges connecting them, each hinge comprising two parts having cylindrically-formed portions embracing a common pintle, a notch in the cylindrical part of one part, and a resilient tongue integral with the other part and adapted to engage the said notch when the members have been swung to a certain position, substantially as described.

11. The combination with two sheet-holding members, of a cover hinged to one of the members, a plurality of hinges connecting the two members, each hinge comprising two parts having cylindrically-formed portions embracing a common pintle, a notch in the cylindrical part of one part, and a resilient tongue on the other part adapted to engage the said notch when the members have been swung to a certain position, substantially as described.

12. The combination with two sheet-holding members, of a cover hinged to one of the members, a plurality of hinges connecting the two members, each hinge comprising two parts having cylindrically-formed portions embracing a common pintle, a notch being provided in the cylindrical part of one part of each hinge, and a spring on the other part adapted to enter the said notch when the members have been swung to a certain position, substantially as described.

In testimony whereof I have signed my name to this specification in the presence of two subscribing witnesses.

JUNIUS B. IRVING.
